UNITED STATES PATENT OFFICE.

JAMES GARFIELD BAIN, OF HELENA, MONTANA.

VALVE FOR RADIATORS.

Application filed April 18, 1922. Serial No. 554,596.

To all whom it may concern:

Be it known that I, JAMES G. BAIN, a citizen of the United States, residing at Helena, in the county of Lewis and Clark and State of Montana, have invented new and useful Improvements in Valves for Radiators, of which the following is a specification.

The object of this invention is to provide a valve for modulated vapor of vacuum heating, one which may be correctly adjusted and which shall be maintained in good condition without the necessity of packing the valve from time to time.

15 A further object is to provide, for cooperation with the valve per se, an element having a plurality of ports of different sizes, this element being set at the point for placing in service that port designed for use 20 when a predetermined extent of radiating surface is employed.

25 A further object is to provide an element of the type specified having ports of different sizes, a valve member for cooperation with said element, and means for determining the exact extent of rotation of the valve member so that it may be opened to the full extent required for a given degree of radiating surface, or may be rotated through a 30 specified angle, depending upon the degree of heat desired.

35 With the foregoing and other objects in view, the invention consists in the novel construction and arrangement of elements described and claimed, it being understood that modifications may be made within the scope of the claims without departing from the spirit of the invention.

40 In the drawings, Figure 1 is a view of the device in vertical section; Figure 2 is a top plan view; Figure 3 is a view in elevation of the sleeve provided with outlet ports of different sizes; Figure 4 is an elevation of the valve member; Figure 5 is a section on line 5—5 of Figure 3; Figure 6 shows the relative size of the ports of the sleeve; Figure 7 shows the top of the casing provided with notches for engagement by a lug on the sleeve of Figure 3, for retaining any 45 port of the sleeve in registration with the outlet member of the casing.

50 The valve casing 10 is provided with threaded connections 12 and 13 and with a threaded portion 14 by means of which the cap 15 is secured.

Carried on element 15 is a plate 16 of annular form, graduated as shown in Figure 2. Valve 18 is provided with an internally threaded bore 19 engaged by the threaded portion of valve stem 20. Secured to the 60 element last named is an annular member 21 constituting a cover, and a threaded element effecting rigid connection between the cover and valve stem. A shank portion 23 is formed on element 21, and a handle 24 is 65 carried by the shank, and permits the setting of the valve 18 in the exact position desired. A pointer 25 cooperates with the graduations on plate 16, and movement from open to closed position involves three-quarters of 70 a revolution.

The valve 18 is provided with a central threaded portion 27, and a Jenkins disk is secured by means of a nut 28, the disk being designated 29, and the latter cooperating 75 with the valve seat 30.

Within valve casing 10 is a sleeve 35 having ports 36, 37, 38 and 39. The port 36 is five-sixteenths of an inch in diameter, the next port is seven-sixteenths of an inch, the 80 third port is five-eighths of an inch, and port 39 is three-fourths of an inch in diameter.

The sleeve 35 is set with the port 36 in registration with the bore 40 of the valve casing, when the extent of radiating surface to 85 be provided for is from fifteen square feet to sixty square feet, but if the radiating surface is from about 105 square feet to 200 square feet, then the sleeve is set so that port 39 will register with opening or bore 90 40 of the valve casing. It will be understood that the intermediate ports provide for radiation surface varying in extent between the limits specified. In order to maintain the sleeve in the exact position desired, so that a given port will be exactly 95 centered, I provide a lug 35' adapted to register with any of the recesses 35² in the valve casing. The washer 43 is notched at one point (not shown), for the lug 35' so 100 that the lug may project below the washer.

Sleeve 35 is provided with a flange 42, and a lead washer 43 is located between this flange and the shoulder 44 of the casing. A lock washer, or ring 45 is located as shown 105 and serves an obvious purpose.

A coiled spring 47 surrounds the valve stem and is interposed between nut 48 and the flange 49 of element 35.

The sleeve 35 is provided with inner ver- 110

tical channels 50 and 51, and the radial members 52 of valve member 18 move vertically in the channels when the valve is shifted by the rotation of the stem.

- 5 Assuming that the sleeve 35 has been properly set and the handle 24 turned so that pointer 25 is at the closed position, indicated by the word "shut" on plate 16 of Figure 2, the handle is to be rotated 10 counter-clockwise to open the valve. When the pointer is opposite graduation 61 the valve is one-quarter open regardless of the particular port of the sleeve 35 then in registration with bore 40 of the casing.
- 15 An important feature of the valve is the disk or washer 66 between the internal flange 49 on the sleeve and the external flange 67 on the stem. This washer keeps the valve in fluid tight condition without renewal except at long intervals.

Having thus described the invention, I claim:

- 20 1. In a device of the class described, a valve casing including an inlet member and an outlet member, a sleeve mounted in the casing, in vertical alinement with the inlet member, a valve member within the sleeve and including a tubular element, a stem threaded into said tubular element for reciprocating the valve member, said sleeve having circumferentially arranged ports of different sizes, the casing being grooved vertically at points having predetermined relation to the ports, means adapted to enter 25 any of the grooves for retaining the sleeve in position for centering any port thereof in alinement with the outlet member, and guiding means between the valve member and the sleeve.
- 30 2. In a device of the class described, a valve casing including an inlet member and an outlet member, a sleeve within the casing,

the bore of the sleeve having communication with the inlet member, said sleeve being provided with a plurality of circumferentially arranged ports of different sizes, any one of which is adapted to register with the outlet member, the casing being grooved vertically at spaced intervals, an element on the sleeve for engaging the walls of any of the grooves, to hold the sleeve in position for registry of one of its ports with the outlet member, a valve within the sleeve and non-rotatable with reference thereto, rotatable means for moving the valve longitudinally 55 of the sleeve, and a device for showing the extent of rotation.

3. In a device of the class described, a valve casing including inlet and outlet ports, a rotatable flanged sleeve having ports therein, said sleeve being mounted in the casing, and one of the ports of the sleeve registering with the outlet port of the casing at a given time to the exclusion of the other ports of the sleeve, the casing being grooved vertically at spaced intervals, an element on the sleeve for engaging the walls of any of the grooves to hold the sleeve in position for registry of one of its ports with the outlet port, a valve and means for guiding the 60 valve in the sleeve, said valve being adapted to permit fluid to pass into one end of the sleeve and out through one of its ports and through the casing, valve operating means including a flanged stem threaded into the 65 valve, a washer positioned between the flanged portion of the stem and the sleeve, and an adjustably mounted spring bearing on the flanged portion of the sleeve and on the side opposite to that engaged by the 70 washer, and tending to move said flanged stem outwardly.

JAMES GARFIELD BAIN.
